CLAIM

The ornamental design for a food press, as shown and described.

DESCRIPTION

FIG. 1 is a top perspective view of a first embodiment of the food press, showing my new design;

FIG. 2 is a left side elevational view thereof;

FIG. 3 is a right side elevational view thereof;

FIG. 4 is front view thereof.

FIG. 5 is a back view thereof.

FIG. 6 is a top plan view thereof;

FIG. 7 is a bottom plan view thereof;

FIG. 8 is an exploded top perspective view thereof, showing the two components of the food press separated;

FIG. 9 is an exploded bottom perspective view thereof; showing the two components of the food press separated;

FIG. 10 is a top perspective view of a second embodiment of the food press;

FIG. 11 is a left side elevational view thereof;

FIG. 12 is a right side elevational view thereof;

FIG. 13 is front view thereof.

FIG. 14 is a back view thereof.

FIG. 15 is a top plan view thereof; and,

FIG. 16 is a bottom plan view thereof.

The broken lines in the drawings illustrate portions of the food press that form no part of the claimed design.

1 Claim, 16 Drawing Sheets
